APRON

Harry Golomb, Bayonne, N. J.

Application February 3, 1954, Serial No. 28,808

Term of patent 3½ years

(Cl. D3—26)

To all whom it may concern:

Be it known that I, Harry Golomb, a citizen of no country, residing in Bayonne, county of Hudson, and State of New Jersey, have invented a new, original, and ornamental Design for an Apron, of which the following is a specification, reference being had to the accompanying drawing, forming part thereof, wherein:

I claim:

The ornamental design for an apron, substantially as shown.
